(57) **CLAIM**

The ornamental design for a divider for containers, as shown and described.

DESCRIPTION

Fig. 2.1 : is a top perspective view of a divider for containers, showing my new design.

Fig. 2.2 : is a top plan view thereof.

Fig. 2.3 : is a front elevation view thereof.

Fig. 2.4 : is a bottom plan view thereof.

Fig. 2.5 : is a cross-sectional view (taken along line A-A in 2.2) thereof.

Fig. 2.6 : is a cross-sectional view (taken along line B-B in 2.2) thereof.

Fig. 2.7 : is an exploded view thereof.

The parts shown by means of broken lines in the reproductions are not part of the claimed design; the back view, left side view and right side view are omitted because they are identical to the front view.
